UNITED STATES PATENT OFFICE.

CHARLES H. HILLIARD, OF CHICAGO, ILLINOIS.

PENCIL-HOLDER.

SPECIFICATION forming part of Letters Patent No. 269,056, dated December 12, 1882.

Application filed January 23, 1882. (No model.)

To all whom it may concern:

Be it known that I, CHARLES H. HILLIARD, residing at Chicago, in the county of Cook and State of Illinois, and a citizen of the United States, have invented a new and useful Improvement in Pencil-Holders, of which the following is a full description, reference being had to the accompanying drawings, in which—

Figure 1 is a top view of the device. Fig. 2 is a section at line *x* of Fig. 1, looking to the right. Fig. 3 is a section at line *y* of Fig. 1, looking to the left. Fig. 4 is a front elevation, showing the device attached to some article of clothing and a pencil. Fig. 5 is a section at line *x* of Fig. 4. Fig. 6 is a rear view of the device unattached.

The object of my invention is to provide a cheap, compact, and efficient pencil-holder, which can be easily attached to and detached from a vest or other suitable article of clothing, and which will hold a pencil when inserted therein with reasonable security, so that the pencil will not be liable to fall out from the holder under ordinary conditions, which I accomplish by means of a plate or other suitable piece bent or otherwise formed, as specified, and provided with a pin and a pin-engaging hook or catch upon the back side, the bend in the plate and the pin and the cloth to which the plate is attached forming a socket to receive and hold the pencil, all as hereinafter described.

In the drawings, A represents the front portion of the device, which may be formed from a piece of sheet metal bent or stamped into the form shown, the central portion, *a*, being about a half-circle of suitable size to receive an ordinary pencil.

b is a pin upon the back side of the part A,

which pin is hinged at one end to A, as shown in Figs. 1, 3, and 6, while the other end of the pin can be held by a hook or catch, *c*, on the other end of A, as shown in Figs. 1 and 2.

B represents a piece of cloth or part of an article of clothing—a vest, for example—to which the device is attached ready for use, the bent portion *a* of the part A and the pin and cloth back of this bent portion *a* forming a socket, *d*, to receive a pencil. I make the bend *a* of such size that it will require a little force to push the pencil down into the socket, and the several parts are so formed and arranged that when the pencil has been inserted it will be held by the pressure of the pin and friction of the cloth and bend *a*, so that the pencil will not slip out under ordinary conditions, and so that it will require a little force to withdraw the same from the holder.

The most convenient way to make the part A will be to stamp the same from sheet metal by means of suitable dies.

The pressure on the pencil when in place can be somewhat adjusted by taking up more or less cloth on the pin when fastening the device in place.

What I claim as new, and desire to secure by Letters Patent, is—

A pencil-holder composed of a plate provided with an attaching-pin and a hook or catch, and bent to form a transverse pencil-receiving socket open at its rear, adapted to contact with the fabric of a garment to retain a pencil when the holder is attached, substantially as described.

CHARLES H. HILLIARD.
